UNITED STATES PATENT OFFICE.

JOHN A. KATZENMEYER, OF ELLWOOD CITY, PENNSYLVANIA.

MECHANISM FOR THREADING PIPES, RODS, ETC.

Application filed October 31, 1923. Serial No. 671,892.

In the accompanying drawings forming a part of this specification, Fig. 1 is a front elevation of a die-head embodying the improvements claimed herein; Fig. 2 is a side elevation of the same; Fig. 3 is a sectional elevation on a plane indicated by the line III—III, Fig. 1; Fig. 4 is a sectional elevation on a plane indicated by the line IV—IV, Fig. 3; Fig. 5 is a view on an enlarged scale showing a cutter conveying head; Fig. 6 is a sectional detail view illustrating the slide locking means; Fig. 7 is a view on an abnormally large scale illustrating the manner of mounting the cutter in the carrying head; Fig. 8 is a detail view illustrating the preferred method of forming a cutter; Fig. 9 illustrates another method of forming the cutter; Figs. 10 and 11 are side and end elevations of a cutter.

In the practice of the invention the stand is formed with a base 1 adapted to slide along guides towards and from the rotatable chuck and with a vertical portion or die stand 2 carrying the parts hereinafter described. The means preferably employed for shifting the cutters radially consists of a cam plate 3 rotatably supported on a hollow central boss 4 on the vertical portion of the stand 2 and is held in place by a plate 5 or die head 5 bolted to the portion of the die stand. As shown in Figs. 3 and 4 the cam plate is arranged in an annular recess formed between the die stand 2 and the plate 5, which is secured to the die head by bolts 5^a. This cam plate is provided on a portion of its periphery with teeth 6 for engagement with a pinion whereby the cam plate may be oscillated as hereinafter described. This cam plate is also provided with a plurality of slots 7 so shaped that when the plate is rotated, pins 8 projecting into the slots will be moved radially. The inner ends of the pins engage the slots preferably through the medium of blocks 9 loosely mounted on the pins and having a length greater than their width and having their opposite sides curved to correspond with the curvature of the walls of the slots as shown in Fig. 4. This construction ensures long bearing surfaces between the blocks and the walls of the slots thereby reducing the wearing away of said surfaces to a minimum. The pins 8 project through radial slots 10 in the plate 5 and into engagement with plates or sectors 12 and 13 of the heads carrying the cutters as hereinafter described,

said heads being adapted to slide radially between spaced V-shaped blocks 11 which are preferably formed by radially grooving the face of the plate 5. In order to keep the blocks in alignment with the radial slots 10 in the die head in case of the removal of the pins 8, the blocks are provided with lugs 9^a projecting into said slots as shown in Fig. 3.

The cutter carrying head is preferably formed in two plates or sections, 12 and 13, bolted together. The inner plates or sections 12 extend inwardly beyond the plates or sections 13 and are provided with suitable means for so supporting the cutters 14 as will permit of the rotation of the latter. A preferred construction to that end consists of annular grooves in the plates for the reception of annular ribs 15 on the ends of the cutters as shown in Fig. 3 and Fig. 7. The opposite ends of the cutters are engaged by ribs 15^a on the setting and adjusting caps 16, the caps being drawn towards the plate 12 by means of bolts 17. The caps are provided with grooves in their inner ends for the reception of ribs 18 in the plate 13 of the heads, and have their outer ends toothed for engagement with worms 19 rotatably mounted in bearings 20 on the plate 13 as shown in Figs. 3 and 5. The ribs 18 and the toothed ends of the caps 16 are formed on arcs of circles having their centers coincident with the axes of the bolts 17. The cutter carrying heads are held within the radial grooves formed by the V-shaped blocks 11 by a face plate 21.

In order to effect the rotation of the cutters by the caps 16 when shifted by the worms, means are employed for effecting a positive engagement of caps with the cutters, such for example as a pin 16^a on the caps engaging holes in the ends of the cutter. It will be observed that the range of movement of the caps by the worms is limited and in order to provide for the adjustment of the cutters when reduced in operative length in sharpening, a plurality of holes are formed in the ends of the cutter. When the caps have been turned in adjusting the cutters to their limit, the caps are turned back, and then lifted until the pins are withdrawn from their holes, and the cutter turned on its axis until the pins can be pushed into the next holes of the series.

As shown in Figs. 1 and 5, the cutter is substantially U-shaped and is formed either

2 by bending a steel bar of a substantial length, width and thickness, into the U-shape, as shown in Fig. 8, or by longitudinally slotting a steel cylinder of suitable 5 diameter and length, as shown in Fig. 9. After the shaping operation, ribs are cut in the periphery of the U-shaped block, said ribs being in planes at right angles to the axis of the cutter as shown in Fig. 10, and 10 the latter hardened. It will be observed that the ends of the ribs terminate in the planes of the inner walls of the legs or sides of the cutter, and these ends may be maintained in proper cutting condition by grinding 15 away the surfaces of these walls, as indicated in Fig. 11. It is preferred that the grinding should be so effected that the inner surfaces of the legs will be in planes tangential or approximately tangential to a circle concentric with the axis of the cutter. By thus grinding back the wall of the tool, 20 such wall will form, when the tool is set, the desired acute angle to a plane passing through the axis of the tool and the axis 25 of the pipe being threaded as shown in Fig. 1.

By reference to Fig. 5 it will be seen that the inner ends of the cutter supporting plate 12 are so cut away as to form what might 30 well be termed the setting finger 22, the advance edge of this finger or index being in a plane in which the entering ends of the ribs on the cutters should lie under normal operative conditions. When placing a cutter 35 in position, the advance face α of the latter is brought into coincidence with the advance edge of the setting finger or index 22.

When the ribs on the cutters are so formed 40 as to be in planes at right angles to the axes of the cutters, provision is made for so supporting the cutters in the heads carrying the same that planes coincident with the ribs of the cutters will be at an angle to the axis of the pipe to be threaded, such angle 45 being dependent on the pitch of the thread to be cut. As for example, if it is desired to cut an eight inch thread on a pipe or rod two and one-half inches in diameter, the cutter should be so supported that planes 50 coincident with the ribs of the cutters will form angles of approximately two degrees with planes at right angles to the axis of the pipe or rod. A convenient construction for attaining the proper angular relation 55 of the cutter consists in slightly inclining the face of the plate 12 as shown in Fig. 7. In a full size working device, the divergence 60 of the inclined face of the plate 12 from a plane at right angles to the axis of the pipe, is too small to be clearly shown, and hence Fig. 7 is drawn to an abnormal scale.

The rotation of the cam plate to shift the cutters is effected by a rotatable member 65 adapted to engage the cam plate, as for example by a pinion 23 mounted in a bearing

24 on the portion 2 of the die head and intermeshing with the teeth 6 on the periphery of the cam plate. In the outer face of the pinion is formed a recess 25 for the reception of a disc 26, the wall of the recess and the periphery of the disc being so constructed that when the disc is pressed into the recess, said parts will engage the one with the other and the pinion rotated by the rotation of the disc, which is so mounted on 70 one end of a shaft 27 passing through the pinion as to rotate with the shaft but free to move longitudinally thereof to engage or be disengaged from the pinion. The disc is shiftable on the shaft to engage the pinion 75 by any suitable means, such for example as the nut 28 screwing onto the shaft which is provided with an operating handle or lever 29. In operating these devices to set the cutters to operate on a larger size of 80 pipe or rod, the handle or lever is shifted a suitable distance from right to left in Fig. 1 and thereby the disc 26 being in frictional engagement with the pinion, the cam plate is turned in a direction to move the cutters 85 outward. The nut 28 is then turned to release the disc 26 from engagement with the pinion, and the lever turned forward from left to right until the indicating point 0 on the disc registers with an indication point 90 on the pinion corresponding to the diameter of pipe to be threaded, the series of indications on the pinion being spaced apart according to the various sizes of pipes to be threaded. The disc is then caused to engage 95 the pinion by tightening the nut 28, and the lever again moved to the right against a suitable stop, thus completing the adjustment of the cutters. To adjust the cutters for threading a smaller pipe the disc is first released 100 from engagement with the pinion and the lever turned from right to left until the index 0 registers with the proper mark in the scale on the pinion. The disc is then caused to engage the pinion and the lever 105 returned to normal position.

It is frequently desired to cut a tapering thread on the pipe or rod, of a length greater than the length of the cutters and in such case the cutters must be moved progressively 110 outward. In the construction shown herein the handle or lever 29 is connected, after the cutters have been adjusted as above described, to the upper end of a rod 32 which extends down to so engage a slide 33 arranged in a guide box 34 on the base 10 of the die head, that when a relative movement of the slide and head is effected as hereinafter described, the rod 32 will be moved longitudinally to shift the lever or 115 handle 29 and thereby change the positions of the cutters as hereinbefore described. In the construction shown herein, the lower end of the rod is slotted for the reception of the slide 33 and the rod and slide operatively 120

connected by a pin 35 carried by the legs formed by slotting the rod, passing through an inclined slot 36 formed in the slide so that by the reciprocation of the latter, the rod will be shifted longitudinally. When cutting taper threads, with a machine wherein the head carrying the cutters is moved relative to the chuck, provision is made for holding the slide stationary while the die head advances. In the construction shown, 5 a rod 37 which is fixed to the frame of the threading machine in any suitable manner, passes transversely through a boss 38 carried by the slide 33 and by locking the boss to the rod, the slide 33 will be held stationary while the die head is reciprocated. A 10 convenient method of locking the boss to the rod and also locking the slide to the die head is shown in Fig. 6. As therein shown, 15 the axial opening is formed through the boss and in the outer portion of the bore or opening is inserted a block 39 slotted for the passage of the rod. A screw 40 provided with an operating handle 41 passes through the end of the block into the slot and bears 20 on the rod 37 so that by turning the screw the block will be shifted so that the rod will be gripped between the screw and the end wall of the slot. In order to lock the 25 slide to the die head when cutting non-tapering threads, a shell 42 is inserted in the inner end of the boss and in the shell is arranged a longitudinally movable bolt 43, which is 30 adapted to be forced outward into a hole 44 in the base 1 of the die head by a spring 45. The bolt is connected to the block 39 by a 35 stem 46. The several locking mechanisms are, in Fig. 6, in positions to hold the slide 33 and permit the boss 38 to slide along the 40 rod 37. When it is desired to cut taper threads, the screw is turned in and as the 45 end of the screw bears on the rod 37, the block 39 will be drawn until the inner end of the slot bears against the rod. This outward movement of the block 39 withdraws the bolt from the engagement with the base of the die head.

I claim herein as my invention:

1. In a mechanism for threading pipes, rods, etc., the combination of a die stand 50 having an annular recess therein, a plate provided with cam slots rotatably arranged in said recess, a plate or die head provided with radial slots and secured to the die stand and forming a cover for the recess in the latter, a plurality of cutter carrying heads 55 slidably arranged in radial guide ways on said cover plate or die head, pins extending through the radial slots in this cover plate and having their respective ends in engagement with the slots in the cam plate and with the cutter heads, and means 60 for shifting the cam plate.

2. In a mechanism for threading pipes, rods, etc., the combination of a die stand 65

having an annular recess therein, a plate provided with cam slots rotatably arranged in said recess, a cover plate or die head provided with radial slots secured to the die stand and forming a cover for the recess, a plurality of cutter carrying heads 70 slidably arranged in radial guide ways on the cover plate, pins extending through the radial slots in the cover plate and having their respective ends in engagement with the slots 75 in the cover plate and with the cutter heads, the outer ends of the pins engaging the cutter heads and provided at their inner ends with blocks slidably mounted in the slots in the cam plate, said blocks being provided 80 with lugs engaging the radial slots in the cover plate and means for shifting the cam plate.

3. In a mechanism for threading pipes, rods, etc., the combination of a die stand 85 having an annular recess therein, a plate provided with cam slots rotatably arranged in said recess, a cover plate or die head provided with radial slots secured to the die stand and forming a cover for the recess, 90 a plurality of cutter carrying heads slidably arranged in radial guide ways on the cover plate, pins extending through the radial slots in the cover plate and having their respective ends in engagement with the slots 95 in the cam plate and with the cutter heads, the outer ends of the pins engaging the cutter heads and provided at their inner ends with elongated concavo-convex blocks slidably mounted in the slots in the cam plate, said blocks being provided with lugs engaging 100 the radial slots in the cam plate, and means for shifting the cam plate.

4. In a mechanism for threading pipes, rods, etc., the combination of a die head, a 105 U-shaped cutter block provided with peripheral ribs terminating at the inner surface of the block, a head provided with an extension forming a bearing for one end of the cutter block, a cap rotatably mounted on 110 the head and engaging the upper end of the cutter block and means for rotating the cap to adjust the cutter block.

5. A mechanism for threading pipes, rods, etc., the combination of a die head, a 115 U-shaped cutter block provided with peripheral ribs in planes at right angles to the axes of the block and terminating at the inner faces of the blocks, a radially movable head provided with means for so supporting the cutter block that planes coincident with the ribs on the cutter block will intersect the axis of the article being threaded at angles less than right angles. A cap rotatably mounted on the head and engaging the cutter block and means for rotating the cap 120 to adjust the cutter block.

6. In a mechanism for threading pipes, rods, etc., the combination of a die head, a 130 U-shaped cutter block provided with periph-

eral ribs in planes at right angles to the axis of the block and terminating at the inner faces of the block, a head provided with an extension forming a bearing for one end of the cutter block, the bearing surface of such extension being so inclined that planes coincident with the ribs on the cutter block will when the latter is in operative position, intersect the axis of the article being threaded at angles other than right angles, a cap rotatably mounted on the head and engaging the cutter block, and means for rotating the cap.

7. In a machine for threading pipes, rods, etc., the combination of a die-head, a plurality of cutters adapted to be moved radially of the die head, means for moving the cutters, a rotatable element adapted to shift the cutter operating means, a rotatable shaft having a predetermined arc of rotation and means whereby the shaft may be adjustably connected to the rotatable element whereby the radial movement of the cutters may be varied.

8. In a machine for threading pipes, rods, etc., the combination of a die head, a plurality of cutters adapted to be moved radially of the die head, means for moving the cutters, a rotatable element adapted to shift the cutter operating means, a shaft having a predetermined arc of rotation, a disc adapted to be rotated by the shaft and means for shifting the disc into and out of engagement with the rotatable element whereby the radial movements of the cutter may be varied.

9. In a machine for threading pipes, rods, etc., the combination of a movable die head, a plurality of cutters adapted to be moved radially on the head, a plate rotatably mounted on the head, means interposed between the plate and cutters whereby the latter may be shifted on the rotation of the plate, a rotatable element adapted to rotate the plate, a rotatable shaft and means whereby the shaft may be adjustably connected to the rotatable element, and means operative by and in accordance with the movement of the die head for rotating said shaft.

10. In a machine for threading pipes, rods, etc., the combination of a movable die head, a plurality of cutters adapted to be moved radially on the head, a plate rotatably mounted on the head, means interposed between the plate and cutters whereby the latter may be shifted on the rotation of the

plate, a rotatable element adapted to rotate the plate, a rotatable shaft and means whereby the shaft may be adjustably connected to the rotatable element, and a slide mounted on the die head and operatively connected to the rotatable shaft, and means for preventing the movement of the slide with the die head.

11. In a machine for threading pipes, rods, etc., the combination of a movable die head, a plurality of cutters adapted to be moved radially on the die, a plate rotatably mounted on the head, means interposed between the cutters and plate whereby the cutters may be shifted on the rotation of the plate, a rod operatively connected to the cutter adjusting plate, a slide carried by the die head, and provided with a cam slot, a pin connected to said rod and extending into the slot in the slide, and means for holding the slide from movement with the head.

12. In a machine for threading pipes, rods, etc., the combination of a movable die head, a plurality of cutters adapted to be moved radially on the die, a plate rotatably mounted on the head, means interposed between the cutters and plate whereby the cutters may be shifted on the rotation of the plate, a rod operatively connected to the cutter-adjusting plate, a slide carried by the die head and provided with a cam slot, a pin connected to said rod and extending into the slot in the slide, means for holding the slide from movement with the head, and a stationary bar and means for locking the slide to the bar.

13. In a machine for threading pipes, rods, etc., the combination of a movable die head, a plurality of cutters adapted to be moved radially on the die, a plate rotatably mounted on the head, means interposed between the cutters and plate whereby the cutters may be shifted on the rotation of the plate, a rod operatively connected to the cutter adjusting plate, a slide carried by the die head and provided with a cam slot, a pin connected to said rod and extending into the slot in the slide, and means for holding the slide from movement with the head, and means for locking the slide to the head, a stationary bar and means for simultaneously locking the slide to the bar and releasing the lock between the head and slide.

In testimony whereof, I have hereunto set my hand.

JOHN A. KATZENMEYER.
